(57) **CLAIM**

The ornamental design for a workspace divider, substantially as shown and described.

DESCRIPTION

FIG. 1 is a front perspective view of a first embodiment of the workspace divider.

FIG. 2 is a front view of the embodiment of FIG. 1.

FIG. 3 is a back view of the embodiment of FIG. 1.

FIG. 4 is a left side view of the embodiment of FIG. 1.

FIG. 5 is a right side view of the embodiment of FIG. 1.

FIG. 6 is a top view of the embodiment of FIG. 1.

FIG. 7 is a bottom view of the embodiment of FIG. 1.

FIG. 8 is a front perspective view of a second embodiment of the workspace divider.

FIG. 9 is a front view of the embodiment of FIG. 8.

FIG. 10 is a back view of the embodiment of FIG. 8.

FIG. 11 is a left side view of the embodiment of FIG. 8.

FIG. 12 is a right side view of the embodiment of FIG. 8.

FIG. 13 is a top view of the embodiment of FIG. 8; and,

FIG. 14 is a bottom view of the embodiment of FIG. 8.

The dashed lines illustrate environmental features that form no part of the claimed design.

The dashed-dotted lines bound claimed surfaces and indicate that an overall length of the workspace divider is different in different embodiments.
